UNITED STATES PATENT OFFICE.

JAMES MCNAUGHTON AND ADAM BARDSLEY, OF BRAINERD, MINNESOTA.

OIL-CUP.

SPECIFICATION forming part of Letters Patent No. 377,435, dated February 7, 1888.

Application filed September 1, 1887. Serial No. 248,542. (No model.)

To all whom it may concern:

Be it known that we, JAMES MCNAUGHTON and ADAM BARDSLEY, both of Brainerd, in the county of Crow Wing and State of Minnesota, have invented a certain new and useful Improvement in Oil-Cups, of which improvement the following is a specification.

Our invention relates to oil-cups employed in the lubrication of guide-bars, crank-pins, bearings, &c., of steam-engines and other machinery, and its object is to simplify and economize the construction of the appliance, as well as to facilitate the adjustment of the feed and obviate derangement or accidental variation thereof in service.

To these ends our invention, generally stated, consists in an oil-cup having an elastic bridge which exerts a constant pressure upon the feed-spindle and acts to maintain the same in any desired position of adjustment.

The improvement claimed is hereinafter fully set forth.

In the accompanying drawings, Figure 1 is a side view in elevation of an oil-cup embodying our invention; Fig. 2, a vertical central section through the same; Fig. 3, a plan or top view with the cap and feed-spindle removed; and Fig. 4, a vertical central section showing another form of cap.

In the practice of our invention we provide an oil-cup the body 1 of which is ordinarily cylindrical, but which may be of any other preferred form, and which is provided at the bottom with a central threaded stem or boss, 2, for attachment to the portion of the engine or other machine to which it is to be applied. A feed-passage, 3, for the delivery of the lubricant extends through the stem 2 and through an internal socket, 4, on the base of the cup, 40 being outwardly tapered toward the top of the socket 4 correspondingly with the lower end of a spindle or needle-feeder, 5, by the adjustment of which relatively to the feed-passage the supply of lubricant to the latter is regulated as desired.

The spindle 5 carries a head or hand piece, 6, upon its upper end, by which it may be rotated, and is provided with an external screw-thread, 7, below the head, to engage a corresponding internal thread on the oil-cup, in order to effect its vertical movement when

rotated. As heretofore constructed it has been usual to provide the spindle with a jam-nut to insure its retention in adjusted position, thus involving an element of additional cost and additional manipulation in adjustment. Under our invention the spindle 5 engages and is held, when adjusted, by an internal screw-thread, 8, formed in an elastic bridge, 9, which extends across the upper portion of the cup, 60 and by the clamping pressure which it exerts through the thread 8 upon the spindle, maintains the same in any position in which it may be set, and effectually prevents it from being jarred loose in service, thereby assuring the 65 continuance and uniformity of the feed. The bridge 9 is split or divided by a central transverse slot, 10, cored in the casting, so that its central portion constitutes two half-bosses, which, when threaded, form half-nuts, and the 70 necessary degree of elasticity is imparted by slightly springing it apart by a wedge inserted in the slot 10 and drilling and tapping out the central hole while the half-bosses are thus forced apart. The spindle being then prop- 75 erly fitted, the wedge is withdrawn and the tendency of the half-nut to spring back, by the elasticity of the metal of the bridge, to the position of the bosses as originally formed induces and maintains a compression upon the 80 spindle, which obviates the necessity of a supplemental fastening device and holds the spindle firmly in position when adjusted, without preventing its rotation by hand when required to vary the degree of feed. The cup is, as in 85 the ordinary construction, closed at top by a cap, 11, screwed thereon; or, when applied to guides, a sliding cap, as shown in Fig. 4, may, if preferred, be employed.

We are aware that oil-cups having a rod- 90 feeder held in position by frictional contact within the contracted end of an inclosing-tube have been heretofore known, as well as oil-cups in which the upper end of the spindle is held and steadied by bent arms or elastic wires 95 bearing at their ends against the body, and we therefore disclaim, broadly, the interposition of an elastic element between the feeder and the body of the cup.

We claim as our invention and desire to secure by Letters Patent—

1. In an oil-cup, the combination of a body

and an expansible split or divided elastic bridge connected to the body, and having an internal screw-thread cut within it, substantially as set forth.

5 2. In an oil-cup, the combination of a body, a transversely-divided elastic bridge connected to the body, and having an internal screw-thread forming two half-nuts on opposite sides of the slot or division of the bridge, and a

spindle or feeder externally threaded to engage the half-nuts of the bridge, substantially as set forth.

JAMES MCNAUGHTON.
ADAM BARDSLEY.
